EDWARD C. H. NYE, OF ASCUSHNET, MASSACHUSETTS.

Letters Patent No. 63,172, dated March 26, 1867.

CROSS-BOW.

The Schedule referred to in these Letters Patent and making part of the same.

TO ALL PERSONS TO WHOM THESE PRESENTS SHALL COME:

Be it known that I, EDWARD C. H. NYE, of Ascushnet, in the county of Bristol, and State of Massachusetts, have made a new and useful invention having reference to Cross-Bows; and I do hereby declare the same to be fully described in the following specification and represented in the accompanying drawings, of which—

Figure 1 is a top view; and

Figure 2, a longitudinal section of a cross-bow, provided with my invention.

The nature of such invention consists in the combination of a cross-bow and arrow magazine, and a mechanism for setting and discharging the string of the bow.

In the drawings, A denotes the stock, and B the spring of the cross-bow, *a* being the cord or string of such spring. A magazine, C, for holding a series of arrows to be arranged within it, as shown at *b b b*, in fig. 2, is placed on the upper surface of the stock A, and is connected with such stock by being hinged to the outer end of a rod, *c*, which slides in the stock lengthwise, and is arranged therein in manner as shown in fig. 2. On or about on a level with the bottom of the magazine, a long slot, *d*, goes through the magazine laterally, and has a notch, *e*, extending down from it at its rear end. The cord *a* of the spring B goes through the said slot. There is applied to the magazine, and so as to extend underneath the notch *e*, a movable block or cord-tripper, *f*, which projects below the magazine a depth equal to, or about equal to, the depth of the notch *e*. The tripper should be capable of being moved vertically in the magazine. A bent lever, *D*, arranged with the magazine and the stock as represented, has its fulcrum at *g*, such being a pin going through the stock. The magazine is connected with the lever by a pin, *h*, going through the two. Leading out of the magazine, and on a level with the upper surface of its bottom, is a passage, *i*, for the exit of an arrow while being driven out of the magazine. On laying hold of the lever and moving it forward into the position shown in blue lines in fig. 2, the magazine will be so advanced as to cause the cord *a* at its middle to take or catch into the notch *e*. By pulling the lever backward the magazine will be retracted and will draw on the cord *a* and contract or bend the spring. By continuing to pull the lever back, the magazine may be forced down upon the stock so as to cause the tripper *f* to be pressed down upon the stock and force the cord out of the notch. The cord on being set free will act against the rear end of the lowermost arrow, and expel such arrow from the magazine. Thus the arrows in succession may be discharged from the magazine.

I claim as my invention the combination of the cross-bow, the arrow magazine, and a mechanism for setting and discharging the cord of the spring of the bow, the whole being substantially as hereinbefore described.

E. C. H. NYE.
